LIGHT INTENSITY CONTROL FOR RAILWAY SIGNAL LAMPS

Ralph R. Kemmerer, Swissvale, Pa., assignor to
The Union Switch & Signal Company, Swiss-
vale, Pa., a corporation of Pennsylvania

Application December 10, 1947, Serial No. 790,901

6 Claims. (Cl. 315—274)

1

My invention relates to control of the light intensity of railway signal lamps, and particularly to an arrangement for controlling railway signal lamps to burn at times at a given intensity, and to burn at other times at a given reduced intensity.

In railway signal systems, it is essential, for sake of visibility, that signal lamps burn at a given intensity during the daytime, whereas a reduced intensity of the light from signal lamps is sufficient at night, and may even be preferable because too great intensity of the signal lights at night may cause discomfort to the enginemen. Furthermore, a saving in electric power is effected by burning the signal lamps at a lower intensity at night. Then, too, in event of war, dimout control of railway signal lamps may be required for reducing their light intensity so that they will be less conspicuous, particularly from the air.

One feature of my invention is the provision of novel and improved means for at times lighting signal lamps by alternating current at a given voltage, and for at other times lighting the lamps by alternating current at reduced voltage.

Another feature of my invention is the provision of means for continuing the normal charging rate for a storage battery for signal control and emergency lighting while the lamps are being lighted by alternating current at reduced voltage.

Still another feature of my invention is the provision of means for lighting the lamps by alternating current at reduced voltage, or by direct current, in the event of failure of the lighting control apparatus.

I shall describe one form of apparatus embodying my invention, and shall then point out the novel features thereof in claims.

The accompanying drawing is a diagrammatic view showing one form of apparatus embodying my invention, in which a manually controllable arrangement is provided for supplying alternating current to a power transmission line normally at a given voltage and at other times at a reduced voltage, and in which a normally energized voltage reduction relay becomes deenergized when the transmission line voltage is manually reduced, and a power-off relay becomes released when the transmission line voltage is further reduced, such, for example, as by a failure of the alternating current source, and also in which signal lamps are lighted by current at normal voltage and a storage battery for signal control and emergency lighting is charged at a normal rate when the voltage reduction relay is in its operated condi-

2

tion, and the signal lamps are lighted by current at reduced voltage and the storage battery is still charged at the normal rate when the voltage reduction relay is released.

5 Similar reference characters refer to similar parts in the drawing.

Referring to the drawing, a stretch of single track railway is shown provided with a plurality of signals including signals 1S and 2S for governing traffic movements in opposite directions. The signals may be of any suitable design such, for example, as the color light type, each of which has a green lamp G, a yellow lamp Y, and a red lamp R.

10 The stretch of railway track is divided by insulated joints 3 into sections, including sections a—b and b—c, in a well-known arrangement. Each of these sections may be provided with a track circuit of any suitable type including a source of current such as a battery 4 connected across the rails adjacent one end of the section, and a track relay, designated by the reference character TR with a distinguishing prefix, connected across the rails adjacent the opposite end of the section.

15 A pole-changer relay, designated by the reference character 1PC, may be controlled in a well-known manner to be energized or deenergized according to traffic conditions in advance of signal 1S. A second pole-changer relay 2PC is similarly controlled according to traffic conditions in advance of signal 2S.

20 The lighting of the G, Y and R lamps of each signal is controlled by a signal relay designated by the reference character H preceded by a numeral which is the same as the numeral in the reference character for its signal, each of which has a slow release neutral armature.

25 30 35 Each of the signal relays H may be controlled by a well-known circuit arrangement such, for example, as shown for relay 1H, which includes front contacts of track relays 1TR, 2TR and A2TR, and pole-changing contacts of relay 1PC.

40 45 50 A power transmission line M, comprising conductors 5 and 6, is supplied with alternating current from the secondary winding d of a power transformer P. Primary winding m of this transformer is provided with outer voltage terminals 9 and 11, and with an intermediate voltage terminal 10. Energization of primary winding m of transformer P from terminals BX and NX of a suitable source of alternating current is controlled by a power control relay W.

55 Energization of relay W may be controlled

manually by any suitable means such, for example, as by a control lever V which controls the transmission of carrier current over conductors 1 and 2 of a telephone line L for effecting energization of relay W.

Current from a suitable source having terminals B and N, controlled by lever V, is supplied to an oscillator-amplifier OA which in turn supplies carrier current through a filter aF to telephone line L. This carrier current is fed from line L through a second filter bF to an amplifier, designated by the reference character AM, which in turn supplies current for energizing relay W.

Primary winding m of a lighting and battery charging transformer K is energized by current from power transmission line M. Transformer K has a lighting secondary winding gd, and a battery charging secondary winding cd.

A voltage reduction relay VR is energized by current from secondary winding gd through asymmetric units 5i and 6i. The parts of the apparatus are so proportioned that relay VR is in its operated condition, with its front contacts closed, while relay W is energized, and relay VR becomes released when relay W is deenergized.

A power-off relay PO is energized from secondary winding gd through a transformer oK and a rectifier oC which comprises asymmetric units 1i, 2i, 3i and 4i. Relay PO remains in the operated condition while relay W is either energized or deenergized but relay PO becomes released when there is a further reduction in transmission line voltage such, for example, as when there is a failure of the source which has terminals BX and NX.

While relay VR is energized, lighting current at normal voltage is supplied to the signal lamps. When relay VR becomes released, the lighting current voltage supplied by secondary winding gd of transformer K also becomes reduced, and a resistor 19 is then included in the lighting circuits for adjusting the reduced lighting voltage.

Secondary winding cd of transformer K is provided with outer voltage terminals 12 and 14 and with an intermediate voltage terminal 13. While current of normal voltage is supplied to transmission line M, relay VR is energized, so battery Q is charged at a normal rate from terminals 13 and 14 of secondary winding cd of transformer K, through a rectifier cC which comprises asymmetric units 7i, 8i, 9i and 10i. While current at reduced voltage is supplied to transmission line M, relay VR is released. Battery Q is then charged at the same normal rate from terminals 12 and 14 of secondary winding cd of transformer K.

Asymmetric units 1i to 10i, inclusive may be of any suitable design such, for example, as the well-known half-wave copper oxide rectifier units.

The signal control circuits are energized at all times by current from battery Q. When relay PO becomes deenergized, the signal lamps are also lighted from battery Q. The voltage of the lighting current from battery Q may be adjusted by means of a resistor 31.

Having described, in general, the arrangement and control of the various parts of apparatus embodying my invention, I shall now describe the circuits and operation in detail.

As shown in the drawing, all parts of the apparatus are in the normal condition, that is, the stretch of railway track shown is unoccupied, and so the track relays are energized; traffic conditions in advance of signals 1S and 2S are such

that relays 1PC and 2PC are energized by current of normal polarity; relays 1H and 2H are therefore energized by current of normal polarity; lever V is in its normal or n position; relays W, VR and PO are in their energized or operated condition; lamps G are energized by lighting current at normal voltage; and battery Q is being charged at a normal charging rate.

With lever V in its n position, oscillator-amplifier OA is energized by current from a suitable source having terminals B and N, through contacts 15 and 16 of lever V closed in the normal position. Oscillator-amplifier OA in turn supplies carrier current of a given frequency through filter aF to telephone line L. This carrier current is supplied through a second filter bF to an amplifier AM which in turn energizes relay W.

With relay W energized, primary winding m of transformer P is energized by current passing from terminal BX of the source of alternating current, through the front point of contact 17 of relay W, terminal 9 of primary winding m, through primary winding m, and terminal 11 of primary winding m, to terminal NX of the same source of current. Current at normal voltage is therefore supplied from secondary winding d of transformer P to transmission line M. Primary winding m of transformer K is therefore energized by current of normal voltage from transmission line M, and hence relays VR and PO are energized from secondary winding gd of transformer K, and are in the operated condition.

With relays VR and PO energized, lamps G of signals 1S and 2S are lighted by current at normal voltage, passing from secondary winding gd of transformer K, through contact 18 of relay VR in multiple with resistor 19, front point of contact 20 of relay PO, then by two multiple paths one of which includes lamp G of signal 1S and contact 21 of relay 1H in the normal position and also the front point of contact 22 of relay 1H, and the other one of the two multiple paths including lamp G of signal 2S and contact 21 of relay 2H in the normal position and also the front point of contact 22 of relay 2H, and then by a single path through the front point of contact 23 of relay PO, back to secondary winding gd of transformer K.

With relay VR energized, a normal charging circuit for battery Q is closed, which includes the front point of contact 24 of relay VR, terminals 13 and 14 of secondary winding cd of transformer K and the portion of winding cd which is between terminals 13 and 14, an impedance 25, and rectifier cC.

Relay 1H is energized by a circuit passing from battery Q, through the front point of contact 26 of relay 1PC, contacts 27, 28 and 29 of relays A2TR, 2TR and 1TR, respectively, winding of relay 1H, and front point of contact 30 of relay 1PC back to battery Q. Relay 2H is energized by a similar circuit.

I shall assume that, with apparatus arranged as shown in the drawing, it is decided to reduce the intensity of the light emitted by the signal lamps. A leverman or dispatcher will therefore move lever V from its normal or n position to its reverse or r position, thereby opening contacts 15 and 16 of lever V and thus disconnecting terminals B and N from oscillator-amplifier OA.

Relay W, therefore, becomes deenergized, and hence its contact 17 opens at the front point and becomes closed at the back point.

Primary winding m of transformer P is therefore now supplied with alternating current pass-

ing from terminal BX, through the back point of contact 17 of relay W, terminal 10 of primary winding *m* of transformer P, a portion of primary winding *m*, and terminal 11 of this primary winding, to terminal NX of the same source of current. Reduced alternating current voltage is therefore now applied by secondary winding *d* of transformer P across conductors 5 and 6 of transmission line M.

A reduced voltage is therefore now supplied through transmission line M to primary winding *m* of transformer K, and hence relay VR becomes released, so that its front contacts open.

The signal lighting circuits now differ from the circuits previously described in that the shunt path around resistor 19 through contact 18 of relay VR is open. Alternating current at reduced voltage is therefore now supplied to signal lamps G through resistor 19.

Battery Q is now charged at the normal charging rate by a circuit which includes the back point 24 of relay VR and all of secondary winding *cd* between terminals 12 and 14 of transformer K.

Relays 1H and 2H are now energized by circuits which are the same as the circuits previously described for these relays.

I shall next assume that all parts of the apparatus are again in the normal condition, and that the source of alternating current fails, or that one of the line conductors of transmission line M breaks. Relay PO, as well as relay VR, will now release. Lamps G of the signals will therefore now be lighted by a circuit passing from battery Q, through the back point of contact 23 of relay PO, then by the multiple paths previously described, and then through the back point of contact 20 of relay PO, and resistor 31 back to battery Q. Relays 1H and 2H are still energized by the circuits previously described for these relays.

I shall now assume that all parts of the apparatus are again in the normal condition, and that there is a failure of the control apparatus, so that relay W becomes deenergized. Relay VR will therefore now release its front contacts as before, and the signal lamps will be lighted by current at reduced voltage, as previously described. With relay VR deenergized, battery Q is still charged at the normal rate, as previously described, and signal relays 1H and 2H are still energized.

As has previously been described, when there is a failure of the alternating current source, so that relay PO is in its deenergized condition, lamps G may be lighted at a lower voltage if resistor 31 is adjusted to accomplish that result.

Although I have herein shown and described only one form of apparatus embodying my invention, it is understood that various changes and modifications may be made therein within the scope of the appended claims without departing from the spirit and scope of my invention.

Having thus described my invention, what I claim is:

1. A lighting control arrangement for railway signal lamps comprising, in combination, a power transmission line, a power transformer having a secondary winding connected across the conductors of said transmission line and having a primary winding provided with two outer terminals and an intermediate terminal, a source of alternating current, manually controllable means for at times connecting said source across said two outer terminals and for at other times connecting said source across said intermediate ter-

5 minal and one of said outer terminals, a battery for energizing control means for said signals, a lighting transformer having a primary winding connected across said transmission line and having a lighting secondary winding and a battery charging secondary winding, a voltage reduction relay and a power-off relay energized by current from said lighting secondary winding and arranged for said voltage reduction relay to release when said source is connected with said intermediate terminal and for said power-off relay to release when the voltage of said source is reduced still further below a given magnitude, means controlled by said voltage reduction relay 10 when in its operated condition for lighting said signal lamps by alternating current from said lighting secondary winding at a given voltage and for charging said storage battery from a given portion of said charging secondary winding at a 15 normal rate, means controlled by said voltage reduction relay in its released condition for lighting said signal lamps from said lighting secondary winding through a resistor at a reduced voltage and for charging said storage battery at said normal rate from more than said given portion of said charging secondary winding, and means controlled by said power-off relay in its released condition for lighting said signal lamps by current from said storage battery.

20 30 35 40 45 50 55 60 65 70 75 2. A lighting control arrangement comprising, in combination, a power transmission line, a power transformer having a secondary winding connected across the conductors of said transmission line and having a primary winding provided with two outer voltage terminals and with an intermediate voltage terminal, a source of alternating current, manually controllable means for at times connecting said source across said two outer terminals and for at other times connecting said source across said intermediate terminal and one of said outer terminals, a lighting relay controlled by current from said transmission line to be in an operated or a released condition according as said source is connected across said two outer terminals or across said intermediate terminal and one of said outer terminals, and a lighting circuit controlled by a front contact of said lighting relay connected in multiple with a resistor for supplying lighting current at a given voltage when said lighting relay is in its operated condition and for supplying lighting current at a reduced voltage when said lighting relay is deenergized.

3. A lighting control arrangement comprising, in combination, a power transmission line, a power transformer having a secondary winding connected across the conductors of said transmission line and having a primary winding provided with two outer voltage terminals and with an intermediate voltage terminal, a source of alternating current, manually controllable means for at times connecting said source across said two outer terminals and for at other times connecting said source across said intermediate terminal and one of said outer terminals, a lighting relay controlled by current from said transmission line to be in an operated or a released condition according as said source is connected across said two outer terminals or across said intermediate terminal and one of said outer terminals, a lighting circuit controlled by said lighting relay for supplying lighting current at a given voltage when said lighting relay is in its operated condition and for supplying lighting current at a reduced voltage when said lighting relay is re-

leased, a storage battery, a battery charging transformer having a primary winding energized from said transmission line, means controlled by said lighting relay in its operated condition for charging said battery at a given normal rate by energy from a given portion of a secondary winding of said transformer, means controlled by said lighting relay in its released condition for charging said battery at said normal rate by energy from more than said given portion of said charging secondary winding, and power-off means for supplying lighting current from said battery when said transmission line is deenergized.

4. A lighting control and battery charging arrangement for railway signal lamps comprising, in combination, a power transmission line, a power transformer having a secondary winding connected across the conductors of said transmission line and having a primary winding, a source of alternating current, manually controllable means for at times connecting said source across a first and a second portion of said primary winding in series and for at other times connecting said source across only said first portion, a lighting transformer having a primary winding connected across said transmission line and having a lighting secondary winding and a battery charging secondary winding, a voltage reduction relay energized from said lighting secondary winding and proportioned to be operated for closing a front contact when said source is connected across said two portions of the primary winding of said power transformer but to be released for closing a back contact when said source is connected across only said first portion of said primary winding, a storage battery, a charging circuit for said storage battery including a first and a second portion of said battery charging secondary winding in series and controlled by said back contact of said voltage reduction relay, a second charging circuit for said storage battery including only said first portion of said battery charging secondary winding and controlled by said front contact of said voltage reduction relay, a lighting circuit for lighting said signal lamps by current from said lighting secondary winding at a given voltage or at a reduced voltage according as said source is connected across said both portions or only said first portion respectively of said primary winding of said power transformer, and a circuit responsive to deenergization of said power transmission line for lighting said signal lamps by current from said battery.

5. A lighting control and battery charging arrangement for railway signal lamps comprising, in combination, a power transmission line, manually controllable means for at times supplying alternating current at a given voltage to said

transmission line and for at other times supplying alternating current at a reduced voltage to said transmission line, a transformer having a primary winding connected across said transmission line and having a battery charging secondary winding comprising a first part and a second part and also having a lighting secondary winding, a charging relay energized by current from said lighting secondary winding and proportioned to close a front contact if said transmission line is energized at said given voltage but to close a back contact if said transmission line is energized at said reduced voltage or is deenergized, a storage battery, a charging circuit for said battery controlled by said front contact and including only said first part of said battery charging winding, a second charging circuit for said battery controlled by said back contact and including said first and second parts of said battery charging winding in series, lighting circuit means including said lighting secondary winding for energizing said signal lamps to have a given light intensity if said transmission line is energized at said given voltage but energizing said signal lamps to have a reduced light intensity if said transmission line is energized at said reduced voltage, and other lighting circuit means responsive to deenergization of said transmission line for energizing said signal lamps from said storage battery.

6. A lighting control and battery charging arrangement for railway signal lamps comprising, in combination, a power transmission line, manually controllable means for at times supplying alternating current at a given voltage to said transmission line and for at other times supplying alternating current at a reduced voltage to said transmission line, a transformer having a primary winding connected across said transmission line, a storage battery, means responsive to energization of said transmission line at said given voltage including a given portion of a secondary winding of said transformer and also at said reduced voltage including more than said given portion of said secondary winding of said transformer for charging said storage battery at a given rate, lighting circuit means for energizing said signal lamps from said transformer to have a given light intensity or a reduced light intensity according as said transmission line is energized at said given voltage or at said reduced voltage, and other lighting circuit means responsive to deenergization of said transmission line for energizing said signal lamps from said storage battery.
